(57) **CLAIM**

The ornamental design for a camera, as shown and described.

DESCRIPTION

FIG. 1 is a front perspective view of a camera according to the present invention;

FIG. 2 is a rear perspective view of the camera;

FIG. 3 is a top view of the camera;

FIG. 4 is a front view of the camera;

FIG. 5 is a bottom view of the camera;

FIG. 6 is a rear view of the camera;

FIG. 7 is a right side view of the camera; and,

FIG. 8 is a left side view of the camera.

The broken lines depict portions of the camera in which the design is embodied that form no part of the claimed design.
